GARMENT AND LIKE PRESSES

Stanley Newbery, New Barnet, England, assignor
of one-half to Stanley Newbery Limited, New
Barnet, England

Application September 27, 1949, Serial No. 117,968
In Great Britain October 6, 1948

10 Claims. (Cl. 38—22)

1

This invention relates to garment and like presses for laundry, dry cleaning, and like clothes or cloth pressing operations, and has reference to a machine of known character wherein a pair of fixed lower bucks are disposed longitudinally end to end and a single upper buck is mounted for oscillation about an axis at right angles to the longitudinal arrangement of the lower bucks, to bring the upper buck into the pressing position over each lower buck alternately, in order that while a garment is being pressed on one of the lower bucks the attendant may lay out a garment for pressing on the other buck.

If normal length lower bucks (of, say, 42") are employed in a machine as above outlined, the radius of arcuate movement of the upper buck would require to be so long that the machine would suffer from installation and practical defects. An aim of the present invention is to circumvent this difficulty and provide a garment press unit having a pair of longitudinally disposed lower bucks, including bucks of normal or greater length, alternately covered by a single upper buck oscillable about an axis of relatively short radius such as is suitable for co-operation with lower bucks of normal or greater length.

The invention consists in a garment or like press having an oscillable upper buck adapted to co-operate alternately with each of a pair of lower bucks for the purpose indicated wherein the upper buck is oscillable at relatively short radius and each of the lower bucks is displaceable towards the path of the upper buck at its extremes of oscillation.

The invention also consists in a garment or like press having an oscillable upper buck adapted to co-operate alternately with each of a pair of lower bucks for the purpose indicated wherein the upper buck is oscillable at relatively short radius and each of the lower bucks is alternately displaceable to locate such in position adjacent the path of the upper buck preparatory to the pressing operation.

The invention further consists in a garment or like press having an oscillable upper buck adapted to co-operate alternately with each of a pair of lower bucks wherein a substantially rectilinear upper buck is oscillated at relatively short radius and each of the lower bucks is substantially rectilinear and wherein relative displacement towards one another is provided between the upper buck and each of the lower bucks alternately at the extremes of the path of oscillation of the upper buck.

2

As an example of the phrase "relatively short radius" a radius of about 4 feet may be taken as typical but it is to be understood that this dimension may be increased or decreased somewhat while still achieving the desired result.

When in pressing relationship a bringing together of a positioned lower buck and the upper buck may be effected for imposing the pressing pressure and in one form of the invention, it is preferred for this purpose to impart a power movement to the upper buck radially while the lower buck is held; in another form the upper buck is held while the co-acting lower buck carries out the power movement.

15 In the accompanying drawings:

Figure 1 is a front view of one embodiment of a garment press according to the invention,

Figure 2 is an end view,

Figure 3 is a rear view of the radial arm shown in a central or neutral position,

Figure 4 is a detail of the supporting links of a lower buck looking in the direction of arrow x in Figure 1,

Figure 5 is a front view of another embodiment of a garment press according to the invention, and

Figure 6 is a side elevation of the press shown in Figure 5.

In carrying the invention into effect according to one convenient mode, described by way of example, as applied to the production of a garment press for laundry or like work, a hollow pedestal 1 (Figures 1 to 4) is provided on which a table 2 is horizontally mounted. The pedestal may be cast or framed sheet metal or fabricated channel element. The forward portion 3 of the table may be bayed for the convenience of access to the bucks by the attendant and may also serve as a mounting for the usual controls for the press. The rear of the table may have a back plate the upper portion of which may be an arc concentric with the arcuate movement which is imparted to the upper buck 4. Over the table a pair of longitudinally aligned lower bucks 5, 6 are mounted as hereinafter described.

45 In the lower portion of the pedestal 1 bearings 7 are mounted for a rock shaft 8 arranged with its axis transverse to the longitudinal direction of the lower bucks 5, 6 and table 2.

50 Towards the rear end of the shaft 8 an oscillable radial arm structure 9 of channel or twin lever form for supporting the upper buck 4 is fixedly mounted. At the upper end of this radial arm 9 a lever 10, 11 of bent or bell-crank form is pivotally secured. The shorter arm 10

of the bell-crank lever extends forwardly over the table and above the lower bucks 5, 6 and has the upper buck 4 resiliently secured thereto so that it extends at right-angles to the lever arm 10 on each side thereof and may overlie each lower buck 5, 6 in turn. The longer arm 11 of the bell-lever 10, 11 extends downwardly and is partially housed between the twin levers of the radial arm 9. Means are provided for giving a pressing displacement to the bell-crank lever 10, 11 to move the upper buck 4 downwardly upon one or other side of the lower bucks 5, 6. One convenient means of imparting motion to the bell-crank lever 10, 11 is a toggle and crank motion. The lower end of the bell-crank arm 11 is connected to a toggle linkage 12, 13 the fixed pivot 14 of which is mounted upon the twin levers of the arm 9 while the central pivot 15 of the toggle is connected to the piston rod 16 of a piston moving in a compressed air cylinder 17 coupled to the usual supply for operating a garment press. The outward end 18 of the cylinder 17 may be pivotally mounted between the twin levers of the arm 9 and to a fitting 19 to which the levers are secured and by which the arm 9 is secured to the shaft 8.

The shaft 8 for the radial arm 9, in that portion which extends into the hollow pedestal 1, has a double armed lever forming a pair of cranks 20, 21 which are displaced symmetrically on either side of the axial plane of the radial arm 9 for operatively displacing the lower bucks 5, 6 in opposite sense.

Alternatively the crank may be in the form of a quadrant plate. In either case the spaced crank pins 22, 23 are pivotally connected to cylinders 24, 25 or slideways in which lower buck actuating rods 26, 27 are guided, each rod having a stop 28, 29 engaged by its cylinder so that upon oscillation of the crank 20 or 21 the respective rod 26 or 27 is thrust upwardly. Compression springs 30, 31 are arranged between the stops 28, 29 and the lower ends of the cylinders 24, 25, the arrangement being such that a certain amount of lost motion is permitted between the cylinders 24, 25 and the rods 26, 27 to accommodate the excess movement of the cranks 20, 21 over and above that which is required to cause the displacement of the lower bucks 5 and 6. The displacement of the lower bucks 5, 6 in opposed directions is obtained by the disposition of the pivots 22, 23 on the opposite side of the shaft axis.

The radial arm 9 may be oscillated to and fro through a predetermined angle which in the present case is preferably about 45°. This oscillation may be imparted by a piston and cylinder, making use of the pneumatic system common in garment presses but it is preferred to impart this motion to the radial arm mechanically from a motorised crank, or eccentric. Thus the shaft 32 is coupled by a rod or linkage to the radial arm 9 at a suitable distance from its axis. The linkage incorporates an eccentric 33 on the shaft 32 and a coupling rod 34 which is pivoted at its lower end by a pin 35, to the fitting 19 of the arm 9.

The shaft 32 forms the output shaft of a reduction gear box 36 driven by belts 37 from a motor unit 38 having suitable clutch means. This arrangement is preferred as such is independent of any rise or fall in the pneumatic pressure of the system, and it will be appreciated, owing to the position of the eccentric 33, that the travel of the upper buck 4 will accelerate from one pressing position to the mid position and decelerate in

travelling from such to the other pressing position.

The lower bucks 5, 6 are arranged longitudinally end to end and with the radial arm 9 of the upper buck 4 in the mid position (i. e. vertical position); the two bucks 5 and 6 are slightly inclined from the horizontal, their inner ends being tilted a few degrees somewhat above their outward ends. This slight tilting of the two bucks 5 and 6 is not discernable on the scale of illustrations used for the drawings. The inner ends of the bucks 5, 6 lie adjacent one another with a suitable working clearance. In this position it will be seen that the bucks 5, 6 lie as chords to the arc of oscillation of the upper buck 4 and the outward ends of the bucks may cut the arc and extend outwardly beyond such. When the upper buck arm 9 is at the end of its swing the opposite lower buck 5 or 6 is turned to the horizontal position while the other buck 6 or 5 is raised to the pressing position.

The mounting for the lower bucks 5 and 6 are duplicates one of the other; thus it will be necessary only to describe one of such arrangements. The centre of the lower side of the buck has a pair of lugs or flanges 39 which are pivotally secured on an axis parallel to the axis of the radial arm shaft 9, at the outer end of link members 40, the lower ends of which are pivoted at 41 to a suitable frame support 42 which may be common to both bucks 5, 6. This fixed pivotal axis 41 is located in the radial plane passing through the axis of oscillation of the radial arm 9 and the axis of pivotal attachment 43 of the outer end of the link structure 40 to the buck when the buck is raised, so that in the pressing position the link 40 is aligned with the longitudinal axis of the arm 9. Spaced from the central linkage axis 43 a second link 44 located inwardly of the lugs is pivotally attached there to the buck. The lower end of this second link is pivotally mounted at 45 on the frame support 42 and the fixed pivots 41 and 45 of both links at their lower ends are spaced further apart than their pivots to the buck flanges 39 at their upper ends in order that the links instead of being effectively parallel, diverge slightly outwardly towards their lower ends and afford a stable abutment in the pressing position.

Any suitable means may be provided for imparting movement from the crank device 20, 21 of the shaft 8 through the connecting rods 26, 27 in order to give the bucks 5 and 6 an upward displacement into a position in which they lie in a plane substantially parallel to a tangent of the arc of movement of the upper buck 4. According to one convenient mode the second link 44 referred to above is formed with a bell-crank lever extension 46 beyond the pivotal axis 45. The respective rod 26 or 27 from the oscillating arm crank 20 or 21 is pivoted to the lever extension 46, the arrangement being such that as the upper buck 4 is oscillated to and fro, that lower buck 5 or 6 towards which the upper buck is moving is thrust upwardly into the tangential position referred to above, and the oscillating arm shaft 8, the arm 9 and the centre of the buck 5 or 6 lie substantially in a radial plane of the axis of oscillation.

It will thus be seen that the lower bucks 5 and 6 are alternately raised and lowered in synchronism with the arcuate oscillatory movement of the upper buck 4 from one pressing position or the other, and accordingly access to one of the bucks 5 or 6 is always free and unobstructed for laying

but a garment while the other buck is co-operating in a pressing operation.

The linkwork 40, 44 described above is such that the buck 5 or 6 which is in the laying position occupies a substantially horizontal position, moving thereinto as the upper buck radial arm 9 passes the vertical position in moving to overlie the other buck for the pressing operation thereon. The disposition of the links 40, 44 when each buck is raised to the pressing position rigidly takes the pressing thrust. A stop may be conveniently provided which co-operates with one or other of the links 40, or 44 to check each lower buck 5 or 6 in the horizontal position and allow the radial arm crank 20, 21 to proceed to the end of its stroke against the resistance of a spring 36, 37 located in the rod guide cylinder 24 or 25 while on the return movement the first portion thereof is absorbed by the lost motion connection referred to above. As this is taken up the crank cylinder engages the stop 28 or 29 on the thrust rod and through the lever extension 46 of the second link 44, thrusts the buck 5 or 6 into the tangential position ready for the descent of the overhanging upper buck 4 for the pressing operation.

The bayed portion of the table 2 may conveniently be provided with the usual press-button or like controls for the pneumatic operation of the pressing displacement of the upper buck and the oscillation of the upper buck 4. These controls are of known form and are interconnected in such a way that both hands of the operators are occupied when causing the descent of the upper buck in the pressing operation and the arrangement is such that the upper buck 4 cannot be oscillated until the pressing operation is complete. After the pressing operation is complete the upper buck 4 is raised and then the radial arm 9 swings over to the other end of its stroke concurrently with the lowering to the horizontal position of the buck which has just received the pressure, and the raising of the other buck to the pressing location ready for the pressing descent of the upper buck when it has reached the other end of its oscillatory stroke.

The lower bucks 5, 6 may be of the same length, that is to say, for example, the normal 42"; or one of the bucks may be 42" and the other one 52", the extra 10" being added to the outward end, in which case the upper buck is made 52" long and when over the shorter of the lower bucks idly overlaps such on the inward side to the extent of about 10". Where both lower bucks 5, 6 are required to be 52" long the extra length being added outwardly, then the upper buck 4 is made about 62" overall and in each pressing position the upper buck idly overlaps the inward end of the lower buck with which it is co-operating. Furthermore, although the bucks would normally be rectangular in plan it will be appreciated that such may be tapered or of other form according to the nature of the garments to be pressed.

Although in one embodiment it is preferred to employ a radial arm 9 moving about a fixed axis for supporting the upper buck 4, it will be appreciated that a similar effect can be secured by mounting the upper buck upon a pair of parallel or other links in such a manner that the buck has a similar oscillatory movement to bring it alternately over one and the other of the lower bucks which are displaced into the pressing position by suitably modified mounting means.

According, therefore, to a further embodiment of the invention, by way of example, as similarly

applied to a garment press for laundry or like work, a supporting pedestal 101 (Figures 5 and 6) is provided on which a table 102 is horizontally mounted. The pedestal may be cast or framed sheet metal or fabricated channel element. The forward portion 103 of the table may be bayed for the convenience of access to the bucks by the attendant and may also serve as a mounting for the usual controls of the press. Over the table a pair of longitudinally aligned lower bucks 105, 106 are mounted as hereinafter described.

In the lower portion of the pedestal 101 bearings 107 are mounted for a rock shaft 108 arranged with its axis transverse to the table 102 and longitudinal arrangement of the lower bucks 105, 106. At or towards the rear end of the shaft 108 is fixedly mounted one link 109 of a pair of parallel oscillable radial links which carry the upper buck 104 and of which the other link 110 is similarly carried by a shaft 111 mounted on bearings 112 in the pedestal 101 similarly to and symmetrical with the bearings 107 of the shaft 108. At their upper ends each of the links 109, 110 carries an upper buck supporting arm, 113 or 114, respectively, each in the form of a shaft pivotally mounted in bearings 115 and 116 at the ends of the links. The two arms 113 and 114 carry a locking bracket 117, to be described hereafter, and a mounting bracket 118 to which the upper buck 104 is resiliently secured.

The links 109 and 110 are equal in length and the spacing between the axes of the arms 113 and 114 is equal to the spacing between the axes of the shafts 108 and 111, so that the links 109, 110 comprise a parallel link mounting which, on oscillation of the links about their lower shafts 108 and 111, will maintain the upper buck 104 substantially horizontal and parallel with the plane of the lower bucks 105 and 106.

To impart oscillation to the parallel links through a predetermined angle, in the present instance approximately 58°, any convenient suitable mechanism may be employed which, as illustrated, comprises a motorised crank and eccentric as shown in the press described with reference to Figures 1 and 2. Thus a reduction gear box 119 transmits drive to eccentric 120 on a shaft 121 and to a coupling rod 122 which is pivoted at its lower end by a pin 123 to a crank 124 on the shaft 108. The crank 124 and the mounting collar 125 at the lower end of the link 109 are non-rotatably secured to the shaft 108 as by key 126, 127. The intermittent drive required is conveniently provided by a motor and clutch mechanism 128 under the control of the press operator.

The lower bucks 105 and 106 are mounted on the supporting pedestal 101 by a bracket 129 having a pair of cantilever arms 130 and 131 extending outwardly on either side of the pedestal and each terminating in vertically disposed sleeve 132 which slidably accommodates a supporting post 134 extending downwardly from each of the lower bucks 105 and 106 respectively. At the lower end of each of the posts 134, a toggle linkage 136 is connected whereby an upward displacement may be given to each of the lower bucks in turn in synchronism with the placing of the upper buck thereover to press the cooperating bucks together. Each toggle linkage is pivoted at its lower end to the supporting pedestal 101 on a bracket 135 and has an operating force applied to its centre pivot 137 in synchronism with the position of the upper buck by any convenient power means, preferably as illustrated, by a fluid displacement piston and cylinder device 138 sup-

ported on the pedestal 101 and operated by a known type of pneumatic control means. The upper end of the toggle linkage 136 may be connected to the lower end of each post 134 by an adjustable head 139 to allow adjustments to the operative throw of each lower buck.

In order to brace or lock the upper buck 104 against movement under the upward pressure of the lower buck 105 or 106, the upper buck 104 or its supporting linkage 109, 110 may be temporarily locked to the pedestal 101, the bracket 129 or to any other convenient rigid and immovable part of the machine by any suitable known form of locking or anchoring device. In the preferred embodiment, the locking or bracing means comprise the previously mentioned locking bracket 111 hung from the upper ends of the links 109, 110 on the arms 113 and 114 and secured against lateral movement thereon by a pair of collars 141. At its lower end the bracket 111 has an aperture 142 adapted to receive a heavy bolt 143 slidingly mounted on a bracket 144 extending outwardly and downwardly from each of the sleeves 132 on the lower buck supporting arms 130 and 131 of the main bracket 129. The bolt 143 is arranged to move in and out of locking relationship with the aperture 142 in the bracket 111 in timed relationship to the previously mentioned upward displacement of the lower bucks in operation. To this end each bolt 143 has an extension piece 145 disposed alongside the lower buck supporting post 134 and provided with a channel 146 inclined to the direction of movement of the bolt. Within the channel 146 is accommodated a roller 147 rotatably mounted on one side of the post 134 as by a shaft 148, such that on upward or downward displacement of the post 134 by the toggle mechanism 136, 138, the roller 147 by engagement in the inclined channel 146 displaces the bolt 143 into and out of engagement with the aperture 142 in the bracket 111, thus, locking the upper buck 104 to the main structure during upward pressing movement of the lower bucks. Rotation of the bolt 143 with respect to its bracket 144 is prevented by a pin and slot guide 149. While the cam action of the roller and inclined channel means has been described above as a preferred form of effecting timed displacement of the locking bolt, it is to be understood that any other suitable known device for effecting such displacement may be utilised.

In operation the upper buck 104 will be moved by the parallel links 109, 110 alternatively over each lower buck, the respective lower buck is then given an upward displacement by means of the toggle mechanism to complete the pressing operation. At the same time, the upward displacement of the lower buck causes the bolt 143 to engage the bracket 111 and so lock the upper buck during the pressing operation. On completion of the pressing operation, the lower buck is moved downwardly from the upper buck disengaging the bolt and allowing the upper buck to be swung across to the other lower buck where the operation is repeated.

I claim:

1. A garment or like press comprising a supporting structure, a pair of lower bucks movably mounted on said structure and normally disposed in a longitudinally aligned end to end relationship, an upper buck having a pressing surface only on the underside thereof and pivotally mounted about a horizontal axis on said structure to be displaceable in a path containing the vertical plane passing through the longitudinal

axes of the lower bucks whereby it can be oscillated to co-operate alternately with each of the lower bucks for pressing purposes, means operating between said structure and said upper buck for oscillating said upper buck about said horizontal axis at relatively short radius on an arcuate path terminating at each end over a lower buck and means operating independently between said structure and each of said lower bucks for alternately displacing each of said lower bucks from their normal dispositions to locate such in a position closely adjacent the upper buck at the end of its arcuate path preparatory to the pressing operation.

2. A garment or like press comprising a supporting structure, a pair of rectilinear lower bucks movably mounted on said structure and normally disposed in a longitudinally aligned end to end relationship, a rectilinear upper buck having a pressing surface only on the underside thereof and pivotally mounted about a horizontal axis on said structure to be displaceable about said horizontal axis in an arcuate path over the lower bucks, means operating between said structure and said upper buck for displacing the upper buck along said path to locate the upper buck at the extremes of said path alternately over and adjacent each of the lower bucks and means operating between said structure and the lower bucks so as to cause a relative displacement between the upper buck and the lower bucks alternately when the upper buck reaches the extremes of said path to bring the adjacent bucks into pressing relationship.

3. A garment or like press comprising a supporting structure, a pair of rectilinear lower bucks movably mounted on said structure and normally disposed in a longitudinally aligned end to end relationship, a rectilinear upper buck having a pressing surface only on the underside thereof and pivotally mounted about a horizontal axis on said structure to be displaceable about said horizontal axis in an arcuate path over the lower bucks, means operating between said structure and said upper buck for displacing the upper buck along said path to locate the upper buck at the extremes of said path alternately over and adjacent each of the lower bucks and means operating between said structure and the upper buck so as to cause a relative displacement between the upper buck and the lower bucks alternately when the upper buck reaches the extremes of said path to bring the adjacent bucks into pressing relationship.

4. A garment or like press comprising a supporting structure, a pair of rectilinear lower bucks movably mounted on said structure and normally disposed in a longitudinally aligned end to end relationship, a rectilinear upper buck having a pressing surface only on the underside thereof and pivotally mounted about a horizontal axis on said structure to be displaceable about said horizontal axis about an arcuate path over the lower bucks, means operating between said structure and said upper buck for displacing the upper buck along said path to locate the upper buck at the extremes of said path alternately over and adjacent each of the lower bucks and means operating between said structure and each of the lower bucks so as to cause each lower buck to be displaced from a loading position in the general line of a common chord of said arcuate path of the upper buck, to alternately occupied 70 pressing locations in which each lower buck in

turn lies parallel to the upper buck at its adjacent extreme of said arcuate path.

5. A garment or like press according to claim 4, wherein the means operating between said structure and each of the lower bucks for effecting displacement of the latter comprise a lever linkage having an operative connection with the means for displacing said upper buck over its arcuate path, each linkage being adapted to displace its associated lower buck to position it in its said pressing location in accordance with the displacements of the upper buck.

6. A garment or like press according to claim 5, wherein for each of the lower bucks said lever linkage comprises a pair of link arms pivoted at spaced points to a lower buck and to a support on said structure, one of said link arms being coincident with the radius of the upper buck when in the pressing location opposite a lower buck and the other of said link arms being provided with a lever extension connected by a coupling rod to the means for displacing the upper buck.

7. A garment or like press according to claim 6, wherein the means for displacing the upper buck over its arcuate path include a horizontally disposed rockshaft journaled in said structure, an arm secured at one end to the rockshaft and at its other end carrying the upper buck, and a two arm lever also secured to the rockshaft, the arms of said lever being connected to said coupling rods for operating the lower buck lever linkages.

8. A garment or like press according to claim 2, wherein the means for displacing the upper buck over its arcuate path include a parallel arm linkage pivotally mounted at its lower end to said structure and carrying at its upper end the upper buck and a horizontally disposed rockshaft jour-

nalled in said structure and secured to the lower end of one of the arms of said parallel arm linkage so that the upper buck when displaced moves parallel to itself.

5. 9. A garment or like press according to claim 8, wherein interengageable means are carried part on said structure in operative association with each of the lower bucks and part on the parallel arm linkage in order to lock the upper buck in its position at each extreme of said arcuate path prior to pressing.

10. A garment or like press according to claim 9, wherein the said interengageable means part which is in operative association with each of the lower bucks include a slideable bolt carried on said structure, and the said interengageable means part on the parallel arm linkage comprises co-operating apertured means with which the bolt can enter into locking engagement, means being associated with said bolt and operated in response to the displacement movement of its associated lower buck for moving said bolt into locking engagement with said apertured means and retracting said bolt after a separating movement is made by the associated lower buck after pressing is completed.
